UNITED STATES PATENT OFFICE.

MARGARET A. WILCOX, OF CHICAGO, ILLINOIS, ASSIGNOR TO THE WILCOX
WATER HEATER COMPANY, OF SAME PLACE.

RADIATOR.

SPECIFICATION forming part of Letters Patent No. 495,284, dated April 11, 1893.

Application filed October 29, 1891. Renewed March 17, 1893. Serial No. 466,542. (No model.)

To all whom it may concern:

Be it known that I, MARGARET A. WILCOX, a citizen of the United States, residing at Chicago, in the county of Cook and State of Illinois, have invented certain new and useful Improvements in Radiators, of which the following is a specification, reference being had therein to the accompanying drawings.

This improvement is designed to provide a heater or radiator that will be convenient and economical in use, not likely to get out of order, and yet comparatively cheap in construction, and the invention consists in the peculiar construction, arrangement and combinations of parts hereinafter more particularly described and then definitely claimed.

In the accompanying drawings—Figure 1 is a front elevation of my improved radiator. Fig. 2 is a view with the front removed, and partly in section, the better to show the pipes, &c. Fig. 3 is a vertical transverse central section of the same.

Referring now to the drawings by figures: 1 represents the back and 2 the front casting, the latter being cast of ornamental form, but the precise configuration may be left to suit the taste of the manufacturer. In the center is a tube or flue 3, preferably oblong in cross section and broadening from a point about two-fifths of its length from the bottom into a pear-shaped combustion chamber 4 open at front, but is closed by a (preferably glass) door 5. Inside of this, and communicating with the gas supply, is a gas pipe 6, having burners 7, of any approved form or style, to burn the gas supplied to said burners through the pipe 6. Although, for greater convenience, I prefer gas, natural or artificial, it is evident that the burners may be of the class known as "vapor burners," in which case gasoline may be supplied to the pipe 6, in any convenient manner.

At 9 and 10 are shown pipes, which lead from and to a heating apparatus, preferably a combined cooker and heater, such as shown in my application, Serial No. 410,239, filed of even date herewith; but I do not limit myself to said heater, as any other may be employed. Starting from the pipe 9, the pipe 50 passes along the bottom of the radiator up the

left side of the chamber 4 and the tube 3, then over to the extreme left of the radiator, thence down to the bottom, along which it passes to the right-hand side of the chamber 4, up said chamber and the tube 3, to the 55 top, thence downward to the bottom, along the bottom to the left side of the chamber 4, up the left side of said chamber and flue as before, across the top, nearly to the left side of the radiator, thence downward, nearly to the 60 bottom, along the bottom to the right side of chamber 4, up the same and the tube, as before, across the top to nearly the right side of the radiator, then down the side, along the bottom, and again up the left side of the chamber 4 65 and pipe 3, and so continuing around down the outside until the end of the pipe, at 10, is reached, which is the return pipe to the heater.

The operation is as follows: The heating 70 apparatus (not shown) being supplied with water and fuel, either solid or gaseous,—the fire is lighted and the gas in the burners 7 also, and a circulation is induced by the joint action of the heater and the burners 7, 75 in the system of piping running from 9 to 10, and more especially by the action of the burners 7 on that portion of the piping contained in the chamber 4 and tube 3, which is exposed to the direct action of the heat from the gas 80 and the heated products of combustion arising therefrom, that pass up the tube 3. The heated products of combustion may pass off through the flue 11 at the top of the tube 3 to the outer atmosphere, or they may pass to a 85 ventilating apparatus, but which, as it forms no part of the invention here claimed, is not described. In some cases, I leave off the glass door 5, and set a reflector 12 behind the gas jets to deflect the heat from them into the 90 room that would otherwise be absorbed by the back of the radiator and the wall behind it. With this arrangement, and with the products of combustion passing out through the flue 11, a very good system of heating and ventilation may be obtained, without the ventilating apparatus above referred to, as air necessary to keep up the combustion of the gas is all drawn in from the cold air lying at the bottom of the room, which is combined with 100

- much carbonic acid gas given off from the lungs of the persons in the room, which is thus carried off as fast as it falls to the floor. The apparatus in this form is thus much like an open fire in its healthful effects, to say nothing of the cheerful aspect of the blazing of the gas, which may be seen through the opening in the front, and which may be heightened, if preferred, by colored glass, or other devices.
- 10 This radiator, in conjunction with my heater, to which reference has heretofore been made, will be found to be very convenient in operation, as it can be used in different ways. For instance, in the fall, or spring, when it may not be necessary to have a very great heat, the water may be kept at a suitable degree of heat to supply the room with the moderate warmth then required, without lighting the gas in the radiator; or should no fire be required in the heating apparatus after the cooking is done, the gas in the radiator will keep up sufficient heat, when the weather is only moderately cool.
- 15 I do not limit myself to the exact construction shown, as it is evident that my invention may be varied in many particulars without departing from the essential features thereof.
- 20 I deem it important that the piping shall be arranged to pass through the heating chamber, then down the outside thereof and again through the heating chamber several times in succession, as by this means a very rapid circulation of the water is kept up, owing to the heat being applied to the pipes at so many different points in the circuit, and for the same reason, all of the radiating pipes are kept at a comparatively even and high heat instead of many of them being cooler than others, as in the old style of pipe radiators.
- 25 I am aware that it has been proposed in a system of supplying heat to cities to reheat the water at different places along the line by separate furnaces, each requiring a separate attendant. This I consider a very different arrangement from mine which is a combined heater and radiator preferably heated by gas, in which there is a continuous circuit

of piping where the water is frequently heated and radiated in one passage through the same radiator.

What I claim as my invention is—

1. A combined heater and radiator inclosed in a single casing and having a heating chamber and a continuous circuit of water piping, several sections of said circuit passing through said heater to absorb heat, and other sections arranged in the circuit between the water heating sections, and acting as radiating surfaces to distribute the heat absorbed by the water, substantially as described. 50

2. The combination in a radiator, of gas burners 7, the tapering chamber 4 inclosing said burners, the flue 3 above said chamber 4, a system of piping lining the walls of said chamber 4 and passing through flue 3, said 55 piping being arranged to pass up through the chamber 4 and flue 3 to heat the water and then down the outside thereof, to act as a radiator, several times in succession in a continuous circuit, thus making a perfect circulation of the water, substantially as described. 60

3. The combination of a radiator casing 2, a central heating chamber 4 therein, a flue 3 above the chamber, a burner within said chamber 4, a system of radiating water piping, passing up through said chamber and flue on one side, out through the flue 3 to the space between the radiator casing and the flue, down said space to act as a radiator, and then again entering the heating chamber and flue and 70 passing up through the same on the opposite side, passes down through the radiator case on the opposite side it first passed down and again up the heating chamber and flue, several times in succession, whereby a continuous circulation is obtained, substantially as described. 75

In testimony whereof I affix my signature, in presence of two witnesses, this 8th day of October, 1891.

MARGARET A. WILCOX.
